UNITED STATES PATENT OFFICE.

GEORGE H. HART, OF WEST HARTFORD, CONNECTICUT.

ELECTRIC SWITCH.

1,180,494.

Specification of Letters Patent. Patented Apr. 25, 1916.

Application filed August 3, 1915. Serial No. 43,357.

To all whom it may concern:

Be it known that I, GEORGE H. HART, a citizen of the United States, residing at West Hartford, county of Hartford, State 5 of Connecticut, have invented a certain new and useful Improvement in Electric Switches, of which the following is a full, clear, and exact description.

My improvement relates to electric 10 switches and has for its object to use a simple and compact oscillating electric switch in which the switch arm member is provided with a chamber containing a spring-pressed ball engaging a peaked cam 15 upon an oscillating actuating member.

The following is a description of an embodiment of my invention, reference being had to the accompanying drawings, in which,

20 Figure 1 is a side elevation of a switch embodying my invention; Fig. 2 is a section of the same on the line 2—2, Fig. 1; and, Figs. 3 and 4 are details showing the switch arm in its two positions.

25 Referring more particularly to the drawings, 1 is the base of the switch having mounted thereon the pivot 2, on which is mounted the actuating member 3 carrying a cam 4 having a high point 5. The cam is 30 arranged so as to be symmetrically disposed relatively to said pivot, the pivot being in the central portion of the actuating member. To the actuating member are pivotally connected push buttons 6—6'.

35 7 is the switch arm journaled at its upper end upon the pivot 2 and having an elongated chamber containing the ball 8 engaged by the spring 9. The axis of said chamber is in line with said cam. At the 40 lower end of the switch arm are contact members 10, which are adapted to engage and disengage stationary contacts 11 forming terminals for the circuit. The pivot 2 is mounted in a frame 12, which is carried 45 by the base, which frame is provided at its lower end with a yoke 13 whose ends 14 constitute abutments which limit the throw of the switch arm in either direction. The push buttons are guided by the plate 15.

50 In the operation of this switch, with the parts in the position shown in Fig. 1, depression of the push button 6 causes the actuating member 3 to move until the high point 5 of the cam 4 passes the ball 8,

whereupon the spring 9 causes the ball 8 to 55 exert a pressure on the opposite side of the high point 5 so as to cause the switch arm 7 to move clockwise so as to open the switch. When the switch is in open position, the depression of the push button 6' causes the 60 parts to operate in a similar manner to move the switch arm counter-clockwise and close the switch.

The switch operates with a quick or snap action in each direction. It is positive 65 in its action and is of a simple and durable construction and can be made of small depth.

As will be evident to those skilled in the art, my invention permits of various modifications without departing from the spirit 70 thereof or the scope of the appended claims.

What I claim is:

1. In an electric switch, the combination of an oscillating actuating member pivoted 75 at its central portion, a peaked cam thereon symmetrically disposed relatively to said pivot, an oscillating switch arm movable about said pivot, said arm having an elongated chamber in line with said cam, a ball 80 and a spring within said chamber, said spring acting to force said ball against said cam.

2. In an electric switch, the combination of an oscillating actuating member pivoted 85 at its central portion, a peaked cam thereon symmetrically disposed relatively to said pivot, an oscillating switch arm movable about said pivot, said arm having an elongated chamber in line with said cam, a ball 90 and a spring within said chamber, said spring acting to force said ball against said cam, and push buttons for actuating said actuating member.

3. In an electric switch, the combination 95 of an oscillating actuating member pivoted at its central portion, a peaked cam thereon symmetrically disposed relatively to said pivot, an oscillating switch arm movable about said pivot, said arm having an elongated chamber in line with said cam, a ball 100 and a spring within said chamber, said spring acting to force said ball against said cam, a frame in which said members are pivoted, said frame having stops limiting 105 the movements of said arm.

GEORGE H. HART.
